UNITED STATES PATENT OFFICE.

BASIL ALFRED SLADE, OF LONDON, AND FREDERICK WILLIAM THOMPSON, OF ASHFORD, ENGLAND, ASSIGNEES OF FORTY-FIVE ONE-HUNDREDTHS TO SAID SLADE, TWENTY-SEVEN AND ONE-HALF ONE-HUNDREDTHS TO SAID THOMPSON, AND TWENTY-SEVEN AND ONE-HALF ONE-HUNDREDTHS TO RESIDENTIAL SMALL HOLDINGS COMPANY LIMITED, OF LONDON, ENGLAND, A CORPORATION OF ENGLAND.

PORTABLE TANK, CESSPOOL, AND THE LIKE.

1,169,688.

Specification of Letters Patent. Patented Jan. 25, 1916.

Application filed June 10, 1913. Serial No. 772,762.

To all whom it may concern:

Be it known that we, BASIL ALFRED SLADE and FREDERICK WILLIAM THOMPSON, both subjects of the King of Great Britain, residing at 27 Charles street, Berkeley Square, London, England, and Birkirrigg, Ashford, Middlesex, England, respectively, have invented new and useful Improvements in Portable Tanks, Cesspools, and the like, of which the following is a specification.

This invention relates to improvements in portable tanks, cesspools and the like and more particularly to cesspools wherein human excreta are subjected to the action of disinfecting, oxidizing or ozonizing fluids or salts and rendered fit for use as a ground fertilizer or manure.

According to this invention, the improved cesspool which comprises a portable tank arranged in communication by means of a suitable detachable joint with the soil-pipe of a water-closet, is provided with a mechanical disintegrating appliance or agitator, and with a discharge valve adapted to control the rate of flow of the contents of the tank.

By subjecting the excreta to salts of manganese, such as permanganate of potash, the urine is sterilized and the feces are oxidized and partly disintegrated; the disintegration being completed by the mechanical disintegrating device. An additional advantage of using permanganate of potash is that the permanganate serves as an oxygen carrier with the mass of excreta and affords a vitalizing and stimulating agent to plant growth.

In order that the present invention may be clearly understood we have hereunto appended explanatory sheets of drawings, wherein—

Figures 1 and 2 illustrate in sectional elevation and plan one form of the improved cesspool, while Fig. 3 illustrates a modified form and Figs. 4 and 5 are details of Fig. 3. Figs. 6 and 7 illustrate modified constructions of the outlet tap or valve.

Referring to Figs. 1 and 2, the cesspool comprises a tank *a* mounted on a suitable carrier *b* and arranged normally under the soil-pipe *c* of a water-closet.

The tank *a* is provided with a cover *a*¹

which may be provided with a water seal as shown in Fig. 1, or may be made to fit snug as shown in Fig. 3. This cover is provided with an annular opening in the center thereof which is provided with suitable packing held in place by means of flanged members. Removably mounted in this opening is a short length of pipe *d*, the upper end of which is made in two parts, which are clamped about the lower end of the soil pipe *c* by screws *d*¹.

An outlet tap or valve *e* is provided at the lower end of the cesspool; such tap being formed with a flared-out inlet *e*¹ covered in front with a grating *e*². A metal ball *f* is inserted in the flared-out mouth-piece in such a manner that a scraper *f*¹ attached to the ball works freely over the grating *e*² on the ball being moved up and down. The movement of the ball is accomplished by means of a lever *f*² and a chain *f*³ connecting said lever to the ball. By moving the ball up and down, an action similar to that of a force-pump is obtained as well as a crushing action whereby the choking up of the outlet passage is insured against.

A mechanical disintegrating appliance comprising a hinged grating or grid *g* adapted, on being vibrated, to agitate or stir up the contents of the tank is also provided. The means for imparting movement to this grating comprises a chain *g*¹ and a lever *g*² but any other suitable means may be employed.

In order to render the tank air-tight, the cover *a*¹ is attached to the body portion *a* by means of a liquid seal supported in a recess or continuous lip *a*² formed around the upper end of the body portion. Suitable shields *j* adapted to slide vertically in guides *j*¹ are also provided on any projecting levers so as to cover the openings through which the same project.

According to the modified construction shown in Figs. 3, 4 and 5, the discharge-passage *e* is covered by two pieces of wire-netting *h* and *l*, the first piece *h* being of fairly wide mesh and fixed directly in front of the discharge-passage, while the second piece *l* is of fairly fine mesh and is adapted to cover a vertically adjustable grid *l*¹. This grid is arranged to slide in slotted guide-pieces *l*².

and is actuated by means of the levers l^3 , l^4 . The grid is moreover provided with prongs l^5 which extend toward the first piece of netting and serve as scrapers. The discharge passage is further controlled by means of a well-known vibratory spring-pressed cover h but any other suitable valve may be employed. The hinged grating or grid g is, in this construction, connected to the operating lever g^2 by means of a link g^3 instead of a chain g^1 as in the former construction.

Fig. 6 shows a modified construction of outlet tap or valve arranged to project through the bottom of the tank a ; the scraper and grid being dispensed with in this case. Fig. 7 shows another modified construction of outlet tap wherein a suspended weight o of rectangular section is employed in place of the ball and flared mouth. The weight slides up and down in the guide box o^1 and is actuated in any suitable manner.

Oxidizing fluids or salts are arranged to be supplied to the contents of the tank in any suitable manner. According to the preferred method, a bottle containing the oxidizing fluid is arranged above the water-closet cistern in such a manner as to charge the incoming flush of water on the cistern being operated.

It is especially advantageous to use permanganate of potash as the oxidizing fluid on account of its relative cheapness and on account of the advantage of potassium for plant growth. The permanganate of potash still continues its chemical action even after the manure has been applied to the earth; the finely divided manganic particles which surround each small part of organic matter having a permanent catalytic action whereby oxygen is liberated to the detriment of putrefying bacteria and protozoa and to the favorable development of aerobic bacteria so that the organic matter is speedily incorporated in the humus as plant food. If it is desired to increase the emanation of oxygen from the manganates, acids, preferably sulfuric acid, may be added to the excreta.

It may here be pointed out that various kinds of manure can be obtained according to the manner in which the tank is operated. For instance, by only slightly removing the ball from its seat, a liquid manure suitable for greenhouse plants is obtained, while on the ball being wholly lifted a liquid containing the finer particles of the solids and suitable for outdoor flowers is obtained. On the ball being retained in its lifted position and the mechanical disintegrator operated, a liquid containing the residue of the excreta suitable for the grosser feeding plants is obtained.

The well-known method of providing against siphonage of the water-closet trap

can be applied to each tank as may be desired.

Claims:

1. A portable sealed tank wherein human excreta are disintegrated comprising an oscillating mechanical disintegrating appliance and means arranged to actuate said appliance, substantially as described. 70

2. A portable sealed tank wherein human excreta are disintegrated comprising an oscillating mechanical disintegrating appliance, a discharge opening in said tank, and means arranged in said discharge opening to reduce the solid excreta to the required consistency, substantially as described. 75

3. A portable tank wherein human excreta are disintegrated, comprising a mechanical disintegrating appliance, and a discharge valve in said tank adapted to control the rate of flow from the contents of said tank, 80 substantially as described. 85

4. A portable sealed tank wherein human excreta are disintegrated, comprising a hinged grating adapted to stir up the contents of the tank, and means for vibrating said hinged grating, substantially as described. 90

5. A portable sealed tank wherein human excreta are disintegrated, comprising a grating hinged to the bottom of said tank, a lever projecting inside and outside of said 95 tank, and means for connecting the free end of said lever to the free end of said grating, substantially as described.

6. A portable sealed tank wherein human excreta are disintegrated, comprising a mechanical disintegrating device, an opening 100 in said tank, a lever connected to said device and projecting outside through said opening, and means for covering said opening, substantially as described. 105

7. A portable tank wherein human excreta are disintegrated, comprising a mechanical disintegrating device, an opening in said tank, a lever connected to said device and projecting through said opening, 110 guides provided at the sides of said opening, and a shield on said lever adapted to slide in said guides and said opening, substantially as described.

8. A portable sealed tank wherein human excreta are disintegrated, comprising a mechanical disintegrating device, means for actuating said device, and a detachable inlet pipe on said tank, substantially as described. 115 120

9. A portable sealed tank wherein human excreta are disintegrated, comprising a mechanical disintegrating device, means for actuating said device, a detachable inlet pipe on said tank, and means for clamping said pipe to the soil pipe of a water closet, substantially as described. 125

10. A portable tank wherein human excreta are disintegrated comprising an oscillating mechanical disintegrating device, 130

means for actuating said device, a discharge passage, and a grid shaped streaming device arranged in front of said passage, substantially as described.

11. A portable tank wherein human excreta are disintegrated, comprising a mechanical disintegrating device, means for actuating said device, a discharge opening, a flared-out discharge pipe projecting inwardly from said opening, a ball arranged in said flared-out discharge pipe, and means for moving said ball, substantially as described.

12. A portable tank wherein human excreta are disintegrated, comprising a mechanical disintegrating device, means for actuating said device, a discharge opening, a flared-out mouth-piece projecting inwardly from said opening, a grating covering said mouth-piece, a ball in said mouth-piece, a scraping device mounted on said ball and extending through said grating, and means for moving said ball, substantially as described.

13. A portable tank wherein human excreta are disintegrated, comprising a detachable two-part inlet pipe, clamping means for securing said pipe to the soil pipe of a water closet, a disintegrating device

hinged to the bottom of said tank, an opening on one side of said tank, a lever connected to said device and projecting through said opening, a discharge opening, a flared-out mouth-piece projecting inwardly from said opening, a grating covering said mouth-piece, a ball in said mouth-piece, a scraping device on said ball and extending through said grating, an opening on the other side of the tank, a lever connected to said ball and projecting through last mentioned opening, and shields on said levers for covering the openings at each side of the tank, substantially as described.

14. A portable tank wherein human excreta are disintegrated comprising a mechanical disintegrating device, means for actuating said device, a discharge opening, a weight arranged directly in front of said opening, and means for moving said weight, substantially as described.

In testimony whereof we have signed our names to this specification in the presence of two subscribing witnesses.
